UNITED STATES PATENT OFFICE.

WILLIAM W. DEAN, OF ROCHESTER, NEW YORK, ASSIGNOR TO STROMBERG-CARLSON
TELEPHONE MANUFACTURING COMPANY, A CORPORATION OF NEW YORK.

TELEPHONE RECEIVER.

1,350,594.

Specification of Letters Patent. Patented Aug. 24, 1920.

Application filed May 10, 1916. Serial No. 96,469.

To all whom it may concern:

Be it known that I, WILLIAM W. DEAN, a citizen of the United States, residing at Rochester, in the county of Monroe and 5 State of New York, have invented a certain new and useful Improvement in Telephone- Receivers, of which the following is a full, clear, concise, and exact description, reference being had to the accompanying drawings, forming a part of this specification.

My invention relates to telephone receivers.

This invention aims to produce a receiver of high efficiency, simple, but rugged construction and low cost of manufacture.

I shall now describe, with the aid of the accompanying drawings, an embodiment of my invention in a direct current receiver.

Figure 1 is a dissected view of a complete 20 direct current receiver;

Fig. 2 is a longitudinal cross section showing the cup, the electro-magnet and the terminal block in section;

Fig. 3 is a rear end elevation of the electro-magnet;

Fig. 4 is a side elevation of the electro-magnet;

Fig. 5 is a perspective view of the terminal block with the terminals mounted there- 30 upon;

Fig. 6 is a front elevation of the cup and the electro-magnet showing the wrench for unscrewing the cup from the shell;

Fig. 7 is a rear elevation of the cup showing the manner of applying the wrench to 35 free the cup from the receiver cap.

The direct current receiver, as illustrated in Fig. 1, comprises the cap 1 and the shell 2 which form the casing of the operating 40 parts inclosed within them. The operating parts comprise the diaphragm 3 and the electro-magnet 4 which electro-magnet is mounted in the cup 5. The cup 5 is provided with a rear threaded portion 6 and a 45 front threaded portion 7 which co-operate with suitable threads in the shell 2 and the cap 1 respectively. The cap 1 holds the diaphragm 3 firmly upon the seat 8 which is formed upon the front edge of the cup.

50 To this end the cap 1 is provided with a

narrow annular ring 9 which, when the cap is screwed in place, lies centrally of the wide seat 8 upon the front of the cup so as to hold the diaphragm 3 as nearly as possible in a plane without strain or tension. 55

Inasmuch as the cap 1 and shell 2 screw upon the cup portion 5, it is obvious that when it is attempted to remove the cap and shell, one or the other will first unscrew and be thus removable. In the event that the 60 cap 1 screws off first, a very poor hold is afforded on the threaded portion 7 for unscrewing the shell 2 from the threaded portion 6, and vice versa in case the shell 2 unscrews first a very poor and ineffective 65 hold is afforded by the threaded portion 6. To overcome this difficulty I provide perforations at 10 and 11. A double ended spanner wrench 13 having a pin 14 adapted to pass into the hole 10 and a pin 15 adapted 70 to engage the hole 11 is provided to remedy the aforesaid difficulty.

The cup 5 is formed of a brass stamping to have a tapered portion 16, a recurved rim portion 17 and a cylindrical portion 18 for 75 receiving the electro-magnet 4. The bottom 19 of the cup is flat to fit the square end of the electro-magnet 4 as can be seen in Fig. 2.

The bottom of the cup is perforated at the 80 center to receive the flat headed screw bolt 20 which passes loosely through the block of insulation 21 and is threaded into the lug or ear 22. A pair of smaller perforations 23-23 are made in the bottom of the cup 85 adjacent the outer edge thereof. A pair of metallic terminals 24-24 are mounted upon the block of insulation 21 and secured thereto by means of the small flat headed screws 25. These terminal pieces 24 are provided 90 with narrow extensions 26 which are stamped up from the sheet metal in a continuous piece with the parts 24. The pins 26 project through the perforations 23 in the bottom 19 of the cup 5 and extend forward to a point a short distance from the open end of the cup to facilitate the attachment to the pins of the terminals of the coil 27 of the electro-magnet 4. The terminal pins 26 are covered with sleeves of insulat- 95 100

ing material 28, as shown in Fig. 2, to prevent grounding or shortcircuiting of these terminals, upon the metal of the cup 5.

The terminal stampings 24 are threaded to receive the terminal screws 29 which hold the terminal clips 30 in place. The terminal clips 30, as can be seen from Figs. 1, 5 and 7, comprise a flat portion 31 which, when the clip is in place, lies upon the face of the terminal stamping 24. A grooved portion 32 has an overhanging lip 33 which lies against the side of the stamping 24 and the block 21, as may be seen in Fig. 7, to prevent the terminal clip 30 from rotating with respect to the terminal stamping 24. The terminal clip 30 forms a universal clip since it is adapted to receive the round end of the wire within the grooved portion 32 or to receive a terminal pin therein, or to receive a flat terminal clip such as is illustrated in Fig. 1 on the tip of the receiver cord, either beneath the clip 30 or beneath the screw 29, as the case may be.

The electro-magnet 4 comprises a series of E-shaped stampings of silicon steel. The bases of these stampings are held together by means of screws 34 and brass clamping blocks 35 into which the screws are threaded. The dimensions of the blocks 35 are such that when the same are clamped in place upon the ends of the stampings 36, the diameter of the compound structure will be such as to fit snugly into the cylindrical bottom portion of the cup 5. A pair of screws 37 pass through suitable openings in the bottom of the cup 5 and are threaded into holes 38 in the brass blocks 35 thereby holding the magnet structure firmly in position in the bottom of the cup. The brass blocks 35 are similar so that only one part need be carried in stock. It will be noted that one of the screws 34 threads into the upper block and one into the lower block.

A spool 39 of insulating material, preferably of bakelite or of bakelized fiber is forced upon the middle limb of the magnet structure and serves to support the coil 27. The end of the magnet structure and the end of the spool 39 are ground off so as to maintain a predetermined distance between the diaphragm 3 which seats upon the edge of the shell and the face of the electro-magnet. I have found that a relatively small number of turns of low resistance wire will give in this structure very good results. I have employed in practice a coil of 300 turns having 5 ohms resistance with highly satisfactory results under severe commercial conditions. While the above proportions have been found well suited for certain purposes where a low resistance is the prime requisite, I do not desire to limit my invention to such proportions but find that the improved construction involving the use of

silicon steel, as herein set forth, enables me to construct highly efficient receivers using windings having many more turns of wire wound on a smaller core. For instance, receivers have been constructed using 1,250 turns of wire which has a resistance of about 35 ohms and which receivers use only half the amount of silicon steel as the low resistance receivers immediately above mentioned.

The receiver which I have described is adapted for rapid assembly under factory conditions. To this end the parts are built up as unit structures which may be readily assembled in final form with a minimum of labor. The electro-magnet structure 4 is built up as a unit, the terminal block portion is grouped as a unit and is then secured to the cup after which the magnet structure is secured to the cup, the terminals of the electro-magnet are soldered to the terminal pins of the terminal block, the receiver cord is then attached and the casing and ear cap screwed in place with the diaphragm in front of the magnet. It is to be noted that the receiver cord has an extension 40 of the jacket thereof which is connected to the lug 22 to relieve the cord of strain.

I have found that the characteristics of silicon steel are peculiarly valuable in direct current receivers, as compared with the best Swedish iron or mild steel heretofore employed. I find that silicon steel has a magnetization curve which rises sharply for relatively low values of current strength as compared with the best material heretofore used. For greater values of current strength the curve flattens out to a greater degree than with the best material heretofore used and finally the steel becomes saturated at a relatively much lower point than prevails in the best material heretofore used.

The result of these features permits the receiver of my invention to operate according to a law of action entirely different from that of prior receivers. I am able to use the receiver successfully on longer lines than has heretofore been possible because it will operate satisfactorily on less current than the best receivers of the prior art. I can use the receiver successfully on heavier current flow than any receiver of the prior art under similar conditions. The characteristics of the steel permit the proper magnetization to be secured with a less number of turns on the magnet and a consequently lower induction. This permits a truer and longer transmission than any receiver heretofore known. And finally this receiver provides such advantageous features that it makes possible a wholly different operation of a telephone system and greatly increases the range and usefulness of such a system.

For instance, on a system having a stand-

ard 24 volt battery the usual prior art receiver on a short line will receive so much current that the diaphragm will be drawn completely against the core of the magnet and rendered useless. On a long line such a receiver will not be sufficiently magnetized to transmit speech.

If the prior art receiver is adjusted when it leaves the factory, for short lines, by 10 lengthening the air gap then the receiver will not operate successfully on longer lines. In any event the receiver of my invention will, with a given air gap, work successfully on short or on long lines and make possible 15 telephone transmission under conditions not heretofore feasible.

What I claim is:

1. In a direct current receiver, a normally non-polarized telephone receiver core of 20 magnetic material, having the characteristic of silicon steel, namely, high magnetization on low current strength and having a relatively flat magnetization curve for higher current strength as compared with Swedish 25 iron.

2. In a direct current receiver, a normally non-polarized telephone receiver core of magnetic material, having the characteristic of silicon steel, namely, high magnetization 30 on low current strength, and relatively low magnetization on higher current strength as compared with Swedish iron.

3. In a direct current receiver, a normally non-polarized telephone receiver core of 35 magnetic material, having the following characteristics, a sharply rising flux curve on low current strengths and a relatively flat flux curve on higher current strengths as compared with Swedish iron.

4. In a direct current receiver, a normally non-polarized telephone receiver core of magnetic material, having the following 45 characteristics, a sharply rising flux curve on low current strengths, and a relatively flat saturation knee as compared with Swedish iron.

5. In a direct current receiver, a normally non-polarized telephone receiver core of magnetic material having a higher permeability 50 on low current strengths, and a low permeability on high current strengths, relative to Swedish iron.

6. In a direct current receiver, a normally non-polarized telephone receiver core of 55 magnetic material having a BH curve of sharper initial rise, and a lower saturation point than a similar curve for Swedish iron.

7. In a telephone receiver, an electromagnet core composed of silicon steel.

8. In a direct current receiver, an electromagnet comprising a laminated core of silicon steel and a winding adapted to be energized by direct current.

9. In a direct current receiver, an electro-

magnet comprising a plurality of sheet 65 metal stampings of silicon steel and a winding adapted to be energized by direct current.

10. In a direct current receiver, an electromagnet having a core comprising a plurality 70 of magnetic conductors of small cross section formed of silicon steel and a diaphragm of magnetic material in operative relation to said electromagnet.

11. In combination a cup having a conical portion and a reduced cylindrical portion, said cylindrical portion co-extending from the reduced end of said conical portion and having a bottom portion, a magnet structure substantially filling said cylindrical portion and resting upon said bottom, 75 said magnet structure having a winding disposed in said cup, a block of insulation secured to said bottom portion, a pair of terminal stampings mounted on said block and having pins extending through said bottom portion and projecting to the said conical portion and sleeves of insulation for said pins.

12. In combination a block of insulation 90 having a hole therethrough to adapt the same to be secured to a receiver cup, a pair of terminal stampings of sheet metal secured to opposite sides of said block, said stampings having narrow extending pins adapted 95 to make connection with the terminals of a receiver winding, said pins being formed integrally with said stampings, screws passing through said flat stampings for securing the stampings to the sides of the block 100 and clips removably secured to said stampings for attaching and connecting the terminals of the receiver cord to said stampings.

13. In combination a prismatic block of 105 insulation, having a hole therethrough, a pair of flat brass stampings secured to each side of said block, said stampings having longitudinally extending pins formed integrally therewith, said stampings being secured to said block of insulation by screws 110 substantially flush with said stampings, a sleeve of insulating material for each of said longitudinally extending pins and removable terminal means secured to said 115 stampings by individual screws for attaching and connecting the terminals of the receiver cord to said stampings and means passing through said hole in the block for supporting the block of insulation.

14. In combination a prismatic block of insulation having a longitudinal opening therethrough to receive an attaching screw for holding the block against a support, sheet metal stampings secured to each side 125 of said block, said stampings having each a portion adapted to cover substantially the side of said block of insulation and having

- also an extending pin integral therewith, a sheet metal terminal clip and a screw for holding said clip to the corresponding stamping, said terminal clip comprising a flat portion adapted to lie upon the face of the stamping and a grooved portion adapted to lie adjacent one edge of the corresponding stamping.
15. In combination a cup comprising a substantially conical portion, a substantially cylindrical portion, a plurality of E-shaped iron stampings, blocks for holding said stampings together, said cylindrical portion of the cup having a closed bottom and a plurality of screws passing through said bottom into said blocks for holding said stampings against the bottom of said cup, said blocks and stampings substantially filling the cylindrical part of said cup.
16. In combination a brass cup comprising a substantially conical portion, a cylindrical portion having a closed bottom joined to said conical portion, the bottom of said cup having an aperture therethrough, said aperture being countersunk upon the inside, a block of insulation, a flat headed countersunk screw passing through said aperture in the bottom of the cup and through said block of insulation, an L-shaped lug having threads coöperating with said screw, said lug having an eye adapted to be secured to the receiver cord.
17. In combination a prismatic block of insulation, a pair of flat terminal members secured on opposite sides of said block, said terminal members being of substantially the full width of the side to which they are attached, screws lying substantially flush with the surface of the terminal members for attaching the terminal members to the block, terminal clips having a flat portion and a grooved portion and means for holding the terminal clips against turning with respect to said terminal members, said terminal clips being connected to and overlying the terminal members.
18. In a direct current receiver, a magnetic system comprising a horse-shoe core and a diaphragm, said horse-shoe core comprising laminations of silicon steel characterized by high permeability at low current strength and low permeability at high current strength as compared with Swedish iron, and a winding upon said core, said winding being adapted to be traversed by direct currents of relatively low current strength having variations corresponding to voice vibrations.
19. In a direct current receiver, a magnetic system consisting of a horse-shoe core and a diaphragm, said horse-shoe core comprising E-shaped laminations of silicon steel, a winding upon the central leg of said E-shaped core, said winding being adapted to be traversed by direct currents of relatively low current strength having variations corresponding to voice vibrations and a diaphragm adapted to be acted upon by the magnetism of said core and being thereby responsive in proper degree either to abnormally high values or abnormally low values of current strength through said winding as compared with the effective range of current strength in a receiver employing a core of Swedish iron.
20. In a telephone receiver the combination of a core comprising laminations of silicon steel, a winding for the core, said winding being adapted to be traversed by currents corresponding to sound waves, and a diaphragm subject to the magnetic flux of said core, said core being characterized by relatively high permeability at low current strength and relatively low permeability at high current strength as compared with Swedish iron, whereby proper operation of the receiver upon abnormally weak sound current or upon abnormally strong sound current is possible, and whereby better definition of sound is secured.
21. In a telephone receiver, a winding adapted to be traversed by voice currents, a diaphragm responsive to the fluctuations of magnetism created by said voice currents, and a relatively stationary magnetic link forming the means for applying the variations of magnetism to the diaphragm to vibrate the same, said magnetic link being composed of a material characterized by relatively high permeability for low values of magnetizing force applied thereto as compared with Swedish iron, whereby the diaphragm is vibrated more vigorously for feeble voice currents and whereby speech transmission to greater distances is permitted.
22. In a telephone receiver, a winding adapted to be traversed by voice currents, a diaphragm responsive to the fluctuations of magnetism created by voice currents, and a relatively stationary magnetic link forming the means for applying the variations of magnetism to the diaphragm to vibrate the same, said magnetic link being composed of a material characterized by relatively high permeability for low values of magnetizing force applied thereto as compared with Swedish iron, whereby the diaphragm is vibrated more vigorously for feeble voice currents and whereby speech transmission to greater distances is permitted, and further characterized by relatively low permeability at high values of magnetizing force applied thereto as compared with Swedish iron, whereby the dia-

phragm is vibrated less vigorously in proportion for voice currents of excessive strength, whereby clearer definition of speech is possible for all values of the strength of the voice currents.

23. A telephone receiver core composed of magnetic material having substantially the characteristics of silicon steel.

24. In a telephone receiver, the combination with a diaphragm, of a core having a pole arranged adjacent to said diaphragm, a winding for the said core, said core being composed of a magnetic material having

substantially the characteristics of silicon steel.

25. In a telephone receiver, the combination with a core composed of a material having substantially the characteristics of silicon steel, a magnetic winding for the said core, and a diaphragm arranged with its midpoint adjacent to the end of said core.

In witness whereof I hereunto subscribe my name this 6th day of May, A. D. 1916.

WILLIAM W. DEAN.
